UNITED STATES PATENT OFFICE.

JOSEPH MARTIN SCHUTZ, OF CHICAGO, ILLINOIS, ASSIGNOR, BY MESNE ASSIGNMENTS, TO CENTRIFIX CORPORATION, OF CLEVELAND, OHIO, A CORPORATION OF OHIO.

CENTRIFUGAL APPARATUS.

Original application filed February 5, 1924, Serial No. 690,861, Patent No. 1,539,435. Divided and this application filed March 3, 1925. Serial No. 12,892.

This application is a division of my original application Serial No. 690,861, filed February 5th, 1924, and is directed to certain forms of the invention which, though disclosed and broadly covered by the original application are not specifically claimed therein.

The invention provides for the centrifugal treatment of substances without resort to rotating parts, and is intended for clarifying, filtering, separating, classifying, grading, concentrating, condensing, heating and distilling various vapors, gases and liquids and the substances therein contained. With these purposes, the invention comprehends the novel devices related thereto, all operating upon a clearly apprehended principle and having a novel generic basis; whereby such purposes and many results and products may be obtained easily, quickly and safely, and by small expenditures of time, money, labor and space.

The invention consists in means employing the pressure or energy of a body or stream of liquid, vapor or gas to set up at a defined point therein a whirling action which assists in collecting and then expelling the substances (gaseous, liquid or solid) that it may be desirable to separate and remove therefrom. Coincidently the stream is first finely subdivided into a large number of thin streams, layers or films by a stationary barrel-like structure or ring that contains a large number of overlapping tangential tuyères. These films are directed tangentially inward and by constant peripheral replenishment both form a whirling body and maintain the whirling action referred to. Each such film or layer in the course of its first action is immediately deflected, and the heavier and the lighter substances making up the film are thus separated by direct centrifugal force and due to the whirling action of the body the light and the heavy substances are prevented from coming together again. The heavier substances are retained directly upon the periphery of the whirling body. From that peripheral position they are continuously moved axially across an imperforate annular surface, thence to be separately discharged under the strong centrifugal impulsion of the main whirling body. The main stream of purified fluid

moves away through an outlet adjacent said imperforate surface; that is, at one end of the restricted space in which the whirling action takes place. In most forms of the invention the imperforate surface takes the form of a centrifugal bowl which contains a large central outlet for the purified fluid. 55 That bowl, like the tuyère ring, is stationary. Under the centrifugal force developed therein, the separated substances are forcibly discharged through one or more openings at or near the periphery of the bowl. 60

Obviously the movement of the main body or stream may be caused by either external pressure or by suction. Only a slight difference of pressure is required; the same yielding a velocity and a suddenness of deflection sufficient to accomplish the centrifugal separation of the several substances. 65

The conveniently small units embodying the invention separately and by multiplication lend themselves to the performance of the smallest and the largest tasks; and, it will be found both objectionable and unnecessary to make or use these units in large, cumbersome or expensive sizes. 70

The invention, and many of its uses, will be readily understood on reference to the accompanying drawings. The description of each structure will generally be restricted to one process or use thereof; easy comprehension of other uses being expected of those skilled in the several arts. 80

In the drawings, Fig. 1. is a perspective sectional view intended to diagrammatically represent the invention;—Fig. 2, is a horizontal section of the tuyère ring portion of the invention;—Fig. 3, illustrates the use of the invention for removing the solids from water, as at the upper end of a turbine penstock;—Fig. 4, is a longitudinal section of the invention in the form of a line separator;—Fig. 5, is a cross section on the line 5—5 of Fig. 4;—Fig. 6, is a modified type of end casting that may be substituted in Fig. 4;—Fig. 7, illustrates a modified form having a single action centrifugal bowl;—Fig. 8, is a vertical section illustrating the application of the invention to the purification of blast furnace gas, or the like;—Fig. 9, is a vertical section illustrating a plurality of the novel devices assembled one upon the other for use in classifying or grading vari- 100 105

ous air-borne products;—Fig. 10, is a vertical section of a special or plural stage water filter employing the invention; and, Fig. 11, is a diagrammatic section better illustrating 5 the use of such filter.

The principles involved and a desirable form of apparatus will be understood almost at once upon an inspection of Figs. 1 and 2. The space A represents any source of liquid, 10 vapor or gas. The pipe B represents any separate space into which the substance from the space A is discharged through a large central outlet opening such as C, but only through the medium or gateway which is 15 provided by the part D, which is a multiple tangential tuyère barrel or ring. This last is coaxial with the outlet opening C and is made up of a number of staves, vanes, or 20 blades, marked d. These are arranged circularly and in relatively tangential overlapping positions. As well shown in Fig. 2, they are separated by narrow spaces or slit-like openings, and thus the tangential entrance ports or tuyères e are formed. All 25 of these ports or narrow passages have the same direction. The cylindrical space F within the tuyère ring, D, is that region within which the before mentioned whirling action is organized and maintained by the 30 movement of the substance from the space A toward the space B. No rotating or moving parts are involved in originating or maintaining the described whirling action. The portion g at the end of, or in other words beyond, the staves d and ports e, is the annular imperforate surface before referred to across which the separated substances are delivered to their outlet. In this case it is 35 a component part of the centrifugal bowl G; 40 constituting the peripheral portion thereof. As shown the bottom of that bowl contains the central outlet C. Leading from the inner periphery of the bowl G is a discharge opening or duct H. This is preferably tangent to the bowl and has the same direction as the slits or ports e; and through this 45 duct the separated substances are discharged from the region (space F) of the whirling action.

50 The effective internal diameter of the tuyère ring and the diameter of the centrifugal bowl as here shown are substantially the same. Both are of greater diameter than the axial outlet C.

55 The opposite closure or end C' has an under or inner surface which is characterized by an annular edge or abutment ring portion, I, that is directly opposite the upper ends of the tuyères or ports e. As to that 60 portion of the fluid which lies close to the inner periphery of the tuyère ring or barrel, the edge portion or abutment I forms the limit of motion in that direction, whereas the bowl G permits relief and motion in its direction and thence parallel to the axis of ro-

tation, and while that rotation is going on. Such are the relations of the closure C' and the bowl G.

As it is often desirable that the outlet of a line-separator shall be positioned at 70 the bottom thereof, an appropriate structure is shown in Figs. 4 to 7. The centrifugal bowl is formed directly in the bottom element 87 of the casing. The latter is completed by the top 88; and, receives the steam 75 or other fluid from the pipe 89. The steam leaves the casing through the outlet 90, but only through the medium of the centrifugal element or ring 91; and the familiar action 80 of the latter discharges the collected moisture and solids into the bowl portion, as before described.

The bowl has a shallow skimming groove or shoulder 92 which receives some of the separated substances. From the bottom 93 of 85 the bowl the lighter of the collected substances are discharged. 92' and 93' are the respective centrifugal outlets. The ring 91 and its cover 91' are fastened to the part 87 by the familiar bolts 94.

In lieu of the bolts 94 the cover plate of 90 the ring may be a part of the casing member 88, as shown by the parts 91' and 88', in Fig. 6, the whole structure being fastened together by the casing bolts 95.

Fig. 7 in addition to showing the modified construction of the casing, exhibits a reversed form cover plate 96 and also the absence of an upstanding rim in the centrifugal bowl 97.

Fig. 8 shows a centrifugal unit (189) used in a cavity (190) provided in the bottom of a blast furnace gas duct 191. The cleaned gas departs through the down pipe 192, which is familiar to all blast furnace operators. As will be observed, Fig. 8 is a sectional view of the dust pocket (193) and the gas pipe (191) common to blast furnaces, the novel apparatus being added thereto. The relation of the bowl 189' to the dust trap 193 is as shown, and the relief duct 194 returns the waste gas to the main duct 191. All other details will be readily understood from the face of the drawing.

Fig. 9 represents a single apparatus that 110 is composed of three of the described centrifugal units having centrifugal bowls of varying shapes to receive and separate different sizes or kinds of substances. Concentrate traps 241, one for each centrifugal bowl 115 are provided and the apparatus constitutes a plural or staged classifier and may be used for ultra-filtration purposes and as a concentrator. Generally it is to be employed for classifying mill products, that are received at the top 242 of the apparatus, accompanied by a stream of gas or liquid, originating at the mill, according to kind. Passing downward through the apparatus, the substances 120 are subjected to repeated whirling actions 125 130

under the varying conditions produced by their tuyère rings and differing bowls; and thus, first, the heaviest of the particles are removed, then those of medium size and weight, and last, the finest of the particles; the clarified carrier-fluid leaving the apparatus through the tail pipe 243.

Figs. 10 and 11 exhibit a series filter of large capacity, and adapted to remove even the finest silts from water and the like. Fig. 10 is an enlarged longitudinal, vertical section of this multiple unit filter and Fig. 11, on a reduced scale, shows the same in operation. The liquid is removed from an elevated reservoir 291 by a hydraulic siphon, 292. By preference the intake end of the siphon is equipped with an open type coarse filter or centrifugal unit 293. In the down-going leg of the siphon is the series or stage filter, 294, about to be described in detail. 295 is the solids waste pipe thereof.

As shown in Fig. 10 the stage filter comprises a plurality of the described centrifugal units of the closed type. The casing 296 of the top unit receives the water from the elbow of the siphon, 292. The intermediate casing 297 receives water from the top and discharges it into the bottom casing, 298. The latter discharges the water into the lower leg 292' of the siphon. Obviously any other means of moving the fluid through the filter may be adopted. The casings may be of the same diameter, but necessarily they increase in height toward the bottom because the tuyère rings of the several units are of substantially the same tuyère capacity though of markedly different diameters. Thus the upper tuyère ring 298 is of large diameter and causes the fluid to slowly swirl in the bowl 298'. The next tuyère ring 299 is of less diameter and obviously causes the liquid to whirl at increased rotative speed in its bowl 299'. Sequentially the lower centrifugal unit 300, being of still smaller diameter, again augments the rotative speed of the moving fluid in the bowl 300'.

Thus the solids of different specific gravities are, so to speak, separately acted upon or graded, with assurance of the final separation of the finest thereof. The collected solids are continuously discharged from the bowls through the familiar tangential outlets, 301, which are connected with the down-pipe 295. Other details of the structure will be read from the drawing in the light of the preceding description. This apparatus may be successfully employed for grading dry materials and either as a dry or a wet concentrator. For both such uses the apparatus should be equipped with concentrate traps similar to those exhibited in Fig. 9.

Having thus described my invention, I claim as new and desire to secure by Letters Patent:—

1. The herein described improvement for

the centrifugal purification of fluids without resort to rotating parts, comprising a circular collecting bowl having a substantially flat bottom provided with a heavy substance outlet at its periphery and having a large central outlet for the purified fluid, in combination with a perpendicular closure axially opposed to said bowl, and a circumferential series of operatively overlapping tangential fluid admission tuyères between said closure and said bowl, serving to whirlingly direct the fluid into said bowl and into said central outlet whereby the heavier substances are collected and discharged through the peripheral outlet while the lighter or purified fluid is whirlingly discharged along the axis of the bowl and outlet and outward through the latter.

2. The herein described improvement for the centrifugal purification of fluids without resort to rotating parts, comprising a circular collecting bowl having a substantially flat bottom provided with a tangential outlet for the heavier constituents of the fluid and having a large central outlet for the purified fluid, in combination with a perpendicular closure axially opposed to said bowl, a circumferential series of operatively overlapping tangential fluid admission tuyères between said closure and said bowl serving to whirlingly direct the fluid into said bowl, against said bottom and into said central outlet and a chamber into which said tangential outlet directs the heavier substances.

3. The herein described improvement for the centrifugal treatment of fluids without resort to rotating parts, comprising a tuyère ring containing a circumferential series of longitudinal inwardly directed and operatively overlapping slit-like tangential tuyères, in combination with a perpendicular closure on one end of said tuyère ring, a second closure of bowl-like shape providing a longitudinal extension for the other end of said ring, said bowl-like closure containing a peripheral outlet for the heavier constituents of the fluid and having a large central outlet smaller than said ring for the lighter or purified portion of the fluid.

4. The herein described improvement for the centrifugal treatment of fluids without resort to rotating parts, comprising a tuyère ring containing a circumferential series of longitudinal inwardly directed and operatively overlapping slit-like tangential tuyères, in combination with a perpendicular closure on one end of said tuyère ring, a second closure of bowl-like shape providing a longitudinal extension for the other end of said ring, said bowl-like closure being of substantially the same diameter as the interior of said tuyère ring, containing a peripheral outlet for the heavier constituents of the fluid and having a large central outlet small-

er than said ring and bowl for the lighter or purified portion of the fluid.

5. The herein described improvement for the centrifugal purification of fluids without resort to rotating parts, comprising a circular collecting bowl having a substantially flat bottom provided with a heavy substance outlet at its periphery and having a large central outlet for the purified fluid, 10 in combination with a perpendicular closure axially opposed to said bowl, a circumferential series of operatively overlapping tangential fluid admission tuyères between said closure and said bowl, serving to whirlingly direct the fluid into said bowl and said central outlet therein and an enclosing casing for directing the fluid into the tuyères of said ring.

6. The herein described improvement for

the centrifugal treatment and grading of 20 fluids without resort to rotating parts, comprising a plurality of centrifugal units each comprising a centrifugal bowl having a central outlet in its bottom and a tangential discharge nozzle at its periphery, together with a circumferential tangential tuyère ring rising from said bowl, a perpendicular top for said ring and a casing 25 surrounding said ring and top, in combination with means for directing the fluid through said units in series, said bowls being of differing formations, and, suitable traps attached to the respective tangential nozzles of said bowls.

In testimony whereof I have hereunto set 35 my hand this 26th day of February, 1925.

JOSEPH MARTIN SCHUTZ.
